US0D1018294S

(12) **United States Design Patent** (10) Patent No.: **US D1,018,294 S**
(45) Date of Patent: ** Mar. 19, 2024

(54) **CONTAINER COVER**

- (71) Applicant: **TARGET BRANDS, INC.**, Minneapolis, MN (US)
- (72) Inventors: **Richard P. Riedel**, Blaine, MN (US); **Terrence J. Hornsby, Jr.**, Minneapolis, MN (US); **Michael M. Habig**, Cincinnati, OH (US)
- (73) Assignee: **TARGET BRANDS, INC.**, Minneapolis, MN (US)
- (**) Term: **15 Years**
- (21) Appl. No.: **29/814,638**
- (22) Filed: **Nov. 8, 2021**

Related U.S. Application Data

- (62) Division of application No. 29/637,483, filed on Feb. 19, 2018, now Pat. No. Des. 937,678.
- (51) LOC (14) Cl. **09-07**

(57) **CLAIM**

The ornamental design for a container cover, as shown and described.

DESCRIPTION

FIG. 1 is a top, perspective view of a container cover in showing a first embodiment of our new design in a closed position;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a top, perspective view of the container cover of FIG. 1 in an open position;

FIG. 9 is a front view thereof;

FIG. 10 is a rear view thereof;

FIG. 11 is a right side view thereof;

FIG. 12 is a left side view thereof;

FIG. 13 is a top view thereof; and

FIG. 14 is a bottom view thereof.

FIG. 15 is a top, perspective view of a container cover in showing a second embodiment of our new design in a closed position;

FIG. 16 is a front view thereof;

FIG. 17 is a rear view thereof;

FIG. 18 is a right side view thereof;

FIG. 19 is a left side view thereof;

FIG. 20 is a top view thereof; and

FIG. 21 is a bottom view thereof.

FIG. 22 is a top, perspective view of the container cover of FIG. 15 in an open position;

FIG. 23 is a front view thereof;

FIG. 24 is a rear view thereof;

FIG. 25 is a right side view thereof;

FIG. 26 is a left side view thereof;

FIG. 27 is a top view thereof; and

FIG. 28 is a bottom view thereof.

The broken lines in the drawings depict the portion of the container and form no part of the claimed design.
